(57) **CLAIM**

The ornamental design for the fastener gun self centering on washer mating contoured ring device, as shown and described.

DESCRIPTION

FIG. 1 is a front perspective view of the holding device of the present invention shown mounted to a fastener gun and prior to engagement with a washer for illustrative purposes; FIG. 2 is a front perspective view of the holding device of the present invention; FIG. 3 is a top plan view of the holding device of FIG. 2; FIG. 4 is a side elevation view of the holding device of FIG. 2 shown prior to engagement with a correspondingly contoured washer for illustrative purposes; and, FIG. 5 is a bottom plan view of the holding device of FIG. 4. The broken lines are for illustrative purposes only and form no part of the claimed design.

1 Claim, 3 Drawing Sheets
